GUNSTOCK MOUNT FOR CAMERAS

Ralph B. Hardy, 365 North 200 East,
Springville, Utah 84663

Filed June 23, 1967, Ser. No. 7,577

Term of patent 14 years

(Cl. D61—1)

FIG. 1 is a side elevational view of a gunstock mount for cameras, showing my new design;

FIG. 2 is a front, top and opposite side perspective view, drawn to a somewhat enlarged scale;

FIG. 3 is a rear elevational view from the standpoint of line 3—3 in FIG. 1, to the same scale as FIG. 1; and

FIG. 4 is a bottom plan view from the standpoint of line 4—4 in FIG. 1, drawn to the same scale as FIG. 2.

The broken line showing of a representative camera, actuator and attachment screw are for illustrative purposes only.

I claim:

The ornamental design for a gunstock mount for cameras, as shown and described.
